[57] CLAIM

The ornamental design for racketball racket frame, as shown and described.

DESCRIPTION

FIG. 1 is a front elevational view of a racketball racket frame embodying our new design;

FIG. 2 is a side elevational view of the embodiment of FIG. 1;

FIG. 3 is a top plan view of the embodiment of FIG. 1; FIG. 4 is a bottom plan view of the embodiment of FIG. 1; and

FIG. 5 is an enlarged fragmentary elevational view of the throat portion of the embodiment of FIG. 1.

The backside of the racketball racket, not shown, presents the same appearance as FIG. 1.
